UNITED STATES PATENT OFFICE.

DUDLEY WRIGHT, OF BANKFIELD, ULVERSTON, ENGLAND.

LIQUID-FUEL FURNACE.

1,290,826.

Specification of Letters Patent.

Patented Jan. 7, 1919.

Application filed September 21, 1917. Serial No. 192,603.

To all whom it may concern:

Be it known that I, DUDLEY WRIGHT, a subject of the King of England, residing at Bankfield, Ulverston, in the county of Lancaster, England, engineer, have invented certain new and useful Improvements in or Relating to Liquid-Fuel Furnaces, of which the following is a specification.

This invention relates to liquid-fuel heated furnaces.

One feature of my invention consists in disposing a producer chamber and furnace side by side, these being separated by a vertical wall, the discharge end of a gasifying tube lying in an aperture extending through said wall.

Another characteristic consists in the use or employment in any suitable liquid-fuel heated furnace (but more particularly a furnace otherwise embodying my improvements) of a gasifying tube or receptacle of the construction hereinafter described.

Further and additional features or characteristics of the invention are described in the specification and pointed out in the claiming clauses appended hereto.

A furnace according to my invention, comprising two portions or chambers arranged side by side, which are separated or divided by a vertical wall or partition wherein are formed an aperture or apertures, ports or passages which are preferably controlled by means of dampers or other suitable movable closures. Within the front or gas producer chamber formed by said vertical wall, there is carried a gasifying tube or receptacle, the discharge mouth whereof extends into a port or passage provided for the purpose in said wall, and within said gasifying receptacle, itself, or pipe connected therewith is disposed a liquid-fuel atomizer preferably of the rotary type, the oil fuel being supplied thereto in any convenient manner. If, as is usually the case, it be desired to pre-heat

the air for supporting combustion of the fuel in the furnace, an air supply pipe is carried through the producer chamber, being preferably coiled on the floor thereof, one end of said pipe being in communication with a fan or other means of transmitting air under pressure and the other end whereof communicates with the gasifying tube or receptacle.

The liquid-fuel may also, if desired, be

conveniently heated in its passage to the atomizer by conducting the supply pipe through the producer chamber.

The gasifying tube or receptacle which I prefer to use is characterized in that the floor thereof is flat, the tube being approximately segmental shape or configuration in cross section reduced or contracted at its discharge mouth, and within same may be formed or fitted a plurality of longitudinally arranged blades or plates; said floor may be roughened, serrated or corrugated or provided with raised ledges or baffles so arranged that any oil which may fall on to the floor shall take a sinuous zig-zag course through the tube or receptacle.

Suitable openings or flues controlled by dampers or the like are provided in the furnace wall or walls, as required.

Said producer chamber is heated (that is the gasifying tube or receptacle and air and fuel pipes are heated) by the flames or heated gases of combustion which pass back from the furnace proper through said ports in the transverse wall.

If it be found desirable or necessary to reduce at certain times the temperature of the producer chamber, I may arrange after closing the flame passage or passages in said transverse wall to conduct the heated gases from the furnace to the producer through an outside flue or flues wherein they are cooled somewhat prior to entering the producer chamber.

My invention may be applied to two or more furnaces, or a double ended furnace, a single producer chamber being common to both or all.

I will further describe my invention with the aid of the accompanying sheets of explanatory drawings which illustrate, by way of examples only, various modes of embodying same.

In said drawings:—

Figure 1 is in longitudinal section.

Fig. 2 a front view partly in elevation and partly in section, and Fig. 3 is a plan of a furnace and a producer chamber integral therewith.

Fig. 4 is a part sectional plan drawn to an enlarged scale as compared with the preceding views, of an atomizer and a portion of the gasifying receptacle, and

Figs. 5, 6, and 7 are respectively sectional

plan, transverse section, and front view, of the gasifying receptacle which I prefer to employ.

Figs. 8 and 9 are, respectively, longitudinal section and front view of a producer and furnace, the former being detachably secured to the latter.

Fig. 10 illustrates in diagrammatic plan view the application of a producer common to two furnaces.

In several views like characters of reference denote like or equivalent parts wherever they occur.

Referring to the drawings, but first more particularly to Figs. 1 to 4, 1 generally designates the combined producer and furnace structure which is constructed of brick work and divided into two portions 2 and 3 by the transverse wall 4 in which are formed the converging ports or passages 5 and 6 controlled by the slidable dampers 7 and 8: 9 represents an air fan and 10 is a pipe leading therefrom and conducted around the floor of the producer chamber 2, being (see Fig. 4) screwed to a flange plate 11 to which plate is also secured the gasifying tube 12. plate 13 indicates an air control valve on the pipe line 10.

Within said gasifying tube 12 is arranged an atomizing receptacle 14 revolvably mounted on an internal pipe 15 which extends through the pipe line 10 and emerges from the pipe line 10 to terminate in a funnel 16 to which oil is supplied from a suitable reservoir 17. The oil discharge pipe 18 from the reservoir preferably terminates as shown above the funnel 16 so that the rate of supply of oil to the atomizing receptacle 14 may be readily ascertained by inspection; but any other sight feeding arrangement may be adopted. On the periphery of the atomizing receptacle are vanes and air under pressure passing through the pipe line is adapted to impinge against the vanes and impart a rotary movement to the atomizing receptacle.

Should the oil supply pipe 15 be made revolvable in the air line 10 and supported by suitable bearings and a packed joint, then a lubricant cup 19 and a tube 20 may be employed to supply a lubricant to the bearings.

21, 22, indicate openings in the furnace walls for charging purposes, which openings are respectively controlled by the counter weighted dampers 23, 24. 25, 25^a indicate inspection openings in the producer chamber 2 respectively controlled by dampers 26, 26^a, and 27 is an inspection opening in the furnace 3 controlled by damper 28.

60 In the floor of the producer chamber 2 and opening 29 controlled by damper 30 is provided; through said opening a lamp may be inserted for heating the gasifying receptacle on the starting up of the furnace.

65 31, 32, are flues leading from the furnace

3 which flues are respectively provided with removable covers 33, 34, and 35 is a flue, provided with removable cover 36 leading from the producer chamber 2. When the furnace is in action the flames from the furnace proper 3 pass through said converging wall passages 5, 6, into the producer chamber 2 thereby heating the gasifying tube or receptacle 12 and also that portion of the air pipe line 10 which lies within the producer chamber.

Referring to Figs. 3 to 7 there is disposed within the iron or steel gasifying tube or receptacle 12 a structure embodying a plurality of plates 37, and at the front or contracted portion 12^a of said receptacle there are formed baffles or ledges 38.

The object of the provision of said longitudinal plates 37 is to provide additional heating area for the fuel passing through the gasifying receptacle and the baffles 38 cause any oil which may drop to the flat floor or base of the receptacle to take a sinuous course therethrough and so, as far as possible, insure its complete gasification prior to leaving the receptacle.

Referring now to Figs. 8 and 9, the producer chamber is constructed of sheet iron or steel and is composed of a front portion or plate 39, a casing portion 40, and outer air or water jacket portions 41, 42. The structure is secured to the furnace proper by the aid of angle plates 43.

In this arrangement the gasifying tube 12 is provided with a flange 12^b whereby it is secured to the front plate 39, the front jacket plate 42 abutting against shoulder 45 and positioned by means of the nuts 44. The air pipe line 10 is arranged to pass around the lower jacket portion 41.

Said producer may be lagged instead of being jacketed if desired.

Referring now to the construction shown in Fig. 10, the producer chamber 2 is common to the two furnaces, 3 3^a, and the pipes 12 enter the producer chamber from opposite sides thereof.

Having now described my invention, what I claim as new and desire to secure by Letters Patent is:—

1. A liquid-fuel heated furnace embodying a producer chamber and a furnace proper arranged side by side, a vertical apertured wall separating said producer chamber and furnace proper, and a gasifying receptacle approximately segmental in cross section passing through said producer chamber and the discharge end whereof lies in an aperture extending through said wall.

2. A liquid-fuel heated furnace embodying a furnace proper and a producer chamber detachably secured thereto, a vertical apertured wall separating said producer chamber and furnace proper, a gasifying receptacle approximately segmental in cross

- section and the mouth whereof is contracted, a plurality of longitudinal plates provided in the interior of said receptacle, and baffle plates on the bottom of said receptacle so that oil falling thereto is caused to take a zig-zag course through said receptacle.
3. A liquid-fuel heated furnace embodying a furnace proper and a producer chamber detachably secured thereto, a vertical apertured wall separating said producer chamber and the furnace proper, and a gasifying receptacle approximately segmental in cross section and the discharge mouth whereof is contracted in the apertured wall.
- 10 4. A liquid-fuel heated furnace embody-

ing a furnace proper and a producer chamber detachably secured thereto, a vertical apertured wall separating said producer chamber and furnace proper, a gasifying receptacle, the mouth whereof is contracted in the apertured wall, and a plurality of baffle plates on the bottom of the receptacle so that oil falling thereto is caused to take a zig-zag course through said receptacle.

20 In testimony whereof I affix my signature 25 in the presence of two witnesses.

DUDLEY WRIGHT.
